UNITED STATES PATENT OFFICE.

JARED LOCKWOOD, OF NEW YORK, N. Y.

DESIGN FOR A SHIRT-SHIELD.

SPECIFICATION forming part of Design No. 28,441, dated March 29, 1898.

Application filed September 28, 1897. Serial No. 653,384. Term of patent 7 years.

To all whom it may concern:

Be it known that I, JARED LOCKWOOD, a citizen of the United States, and a resident of New York city, in the county and State of New York, have invented a new and original 5 Design for Shirt-Shields, of which the following is a specification.

The invention relates to a design for a shirt-shield adapted for men's wear; and I hereby 10 declare that this specification, of which the accompanying drawings form a part, is sufficient to enable any one of intelligence to understand and apply my invention.

In Figure 1 of the drawings I have shown 15 a front view of a shirt-shield embodying the invention represented as folded around the neck of the wearer. In Fig. 2 I have shown a top view of the same with the ends extended. A and A' are the aprons, and B is the neck

portion. C is a collar formed with and constituting part of the shirt-shield and extending around the neck portion and down each of the aprons. It extends part way down the aprons, so as to leave more or less of the ends of the aprons exposed. 20 25

The collar C is the characteristic feature of the design, the same comprising a soft fabric having longitudinal wavy folds or creases C'.

What I claim is—

The design for a shirt-shield having the 30 collar substantially as shown and described.

In testimony whereof I have signed my name to this specification in the presence of two subscribing witnesses.

JARED LOCKWOOD.
